UNITED STATES PATENT OFFICE

LLOYD K. RIGGS, OF NEW BRUNSWICK, NEW JERSEY, ASSIGNOR TO E. R. SQUIBB AND SONS, OF NEW YORK, N. Y., A CORPORATION OF NEW YORK

ANÆSTHETIZING APPARATUS

Application filed March 8, 1926. Serial No. 93,099.

This invention relates to an apparatus for producing gaseous mixtures, and particularly such mixtures as are employed for anæsthetic purposes although the apparatus 5 may be utilized to produce mixtures of any gases in predetermined proportions.

In producing anæsthesia it is usual to administer mixtures of gases such, for example, as mixtures of propylène, oxygen and air, and 10 it is essential that the proportions in which these gases are present in the mixture be definite and predetermined. It is desirable, moreover, that the proportions be regulable in order that the conditions attending the anæsthesia may be properly controlled. Thus, 15 for example, it may be desirable to administer promptly an excess of pure oxygen to revive a patient.

Apparatus has been devised and utilized 20 heretofore for the purpose of administering gaseous anæsthetics and mixtures thereof. Tests conducted with such apparatus have shown that it is unreliable because the proportions of the gases actually delivered in the 25 mixture do not correspond ordinarily with the calibrations of such instruments. It has not been possible heretofore to produce and administer mixtures of gases with assurance that the proportions are definite nor to vary 30 these proportions at will.

It is the object of the present invention to provide a simple and compact apparatus which is capable of delivering a plurality of different gases in predetermined proportions 35 to a common mixing chamber, the apparatus being so arranged that two or more gases can be supplied in the desired proportions.

A further object of the invention is to provide an apparatus in which a rapid flow of 40 one of the gases, for example, oxygen, is permitted under conditions which require the administration of this gas without the necessity of measuring the quantity supplied.

Other objects and advantages of the invention will be apparent as it is better understood by reference to the following specification and accompanying drawing, in which

Fig. 1 is an elevation partially in section of the apparatus embodying the invention;

Fig. 2 is a plan view thereof; and

Fig. 3 is an end elevation of the structure illustrated in Figs. 1 and 2.

In carrying out the invention I employ a plurality of flowmeters discharging into a common mixing chamber and having inclined legs communicating with a common receptacle in which a quantity of liquid is maintained at a predetermined level. Each of the flowmeters comprises a pipe in which a diaphragm having a capillary opening is disposed. Each of the pipes communicates with one of the legs which is normally filled with liquid from the common receptacle with which which all of the legs communicate. This receptacle is connected to the mixing chamber. Each of the pipes communicates with a source of gas under pressure, for example, in a cylinder in which the gas is packed for transportation with a suitable pressure-reducing valve to control the flow 70 of gas therefrom. Thus, the apparatus may be supplied with oxygen, air, propylène, ethylene, nitrous oxide, carbon dioxide or acetylene, or any other gas which is to be utilized either alone or in admixture with 75 one or more of the other gases. When one or more of the valves controlling the supply of gases under pressure is open that gas is permitted to flow through the pipe and thence through the capillary opening in the dia- 80 phragm to the mixing chamber. At the same time the pressure of the gas is exerted upon the liquid in the connected leg and a portion of the liquid is forced thereby into the common receptacle for the liquid, the amount of movement of the liquid in the leg depending upon the difference in pressure on opposite sides of the diaphragms in the several pipes through which the gases enter the apparatus.

By observing the position of the liquid in the several legs with reference to the calibration employed in connection therewith in the form of scales adjacent to the legs, the exact amount of each particular gas entering the mixing chamber can be determined and the 90 valves can be regulated consequently to supply the several gases in any desired proportions. The gases in the desired proportions enter the mixing chamber, are there mingled and are withdrawn and delivered 95 100

through a suitable connection which permits the application thereof for the intended purposes, for example, the application of the gases to produce anaesthesia.

5 In addition to the advantage of exact control of the proportions of the several gases entering the mixing chamber the apparatus has the advantage that when it is desirable to administer a single gas, for example, oxygen without measurement, all of the valves may be closed quickly with the exception of the valve leading to the supply of oxygen. This valve can be opened to supply the gas under sufficient pressure to force all of the liquid 10 from the leg into the liquid receptacle. The gas will pass thence into the mixing chamber which is no longer supplied with other gases and without measurement. Thus it is possible to supply oxygen, for example, in copious quantities in case of emergency by simple manipulation of the valves.

15 The simple form of the apparatus is illustrated in the accompanying drawing. It is supported preferably upon an upright frame 25 of wood or other suitable material and includes a plurality of pipes 6, 7, 8, 9 and 10, each of which terminates near the bottom of the frame in a nipple 11 having a valve 12 therein. Each of the nipples is adapted to be 20 connected through a suitable hose to a source of gas under pressure such as the well known pressure cylinders in which various gases are transported. Inclined legs 13, 14, 15, 16 and 17 are connected to the pipes 6, 7, 8, 9 and 10, these legs being of some suitable transparent 25 material such as glass and having adjacent thereto scales 18 which are calibrated to indicated the volume of the gases flowing through the apparatus as determined by the 30 position of liquid in the legs. The liquid is maintained in a common receptacle 19 with which each of the legs communicates. The receptacle has preferably a glass wall so that the level of liquid therein can be observed. 35 A mixing chamber 20 is connected to each of the pipes 6, 7, 8, and 9 and 10, and to the receptacle 19 through a connection 21. A diaphragm 22 having a capillary opening is disposed in each of the pipes 6, 7, 8, 9 and 10 to limit the amount of gas flowing through 40 the pipe and to maintain a difference in pressure in the gases on opposite sides of the diaphragms so that corresponding differences in pressure exist in the legs 13, 14, 15, 16 and 17 and the receptacle 19. Because of these differences in pressure the position of the liquid 45 in the several legs will be determined by the amount of each gas which is flowing through the apparatus to the mixing chamber 20, and 50 by adjustment of the valves 12 the amount of each gas can be determined accurately and consequently the proportions of the gases in the mixture can be varied at will. The gases are mixed in the mixing chamber 20 prefer- 55 ably with the aid of a spiral vane 23 and the 60

mixture escapes through an outlet 24 which may be connected to the apparatus (not shown) in which the mixture is utilized.

65 The level of liquid in the receptacle 19 is maintained preferably by the introduction thereof continuously through a pipe 25 having a valve 26 and a bowl 27 into which liquid can be permitted to run from any suitable source. The amount of liquid in the receptacle 19 is determined by an overflow pipe 28 75 having a valve 29 and a nipple 30 which may be connected in any suitable way to a waste pipe.

80 The apparatus as described, though simple in structure, permits nevertheless the accomplishment of an object unattained heretofore in the preparation of gaseous mixtures for anaesthetic purposes. It affords assurance of safety in the use of such gases and thus reduces materially the hazards which have accompanied the application of anaesthetic gases 85 in the past. The apparatus is particularly effective because of the ease with which changes in the composition of the gaseous mixture can be accomplished and the readiness with which the changes can be observed. 90 Any modification in the positions of any of the valves controlling the flow of gases through the apparatus is reflected immediately by the changed position of the liquid in the several legs, and by the provision of properly calibrated scales the proportions of gases in the mixture at any given moment can be read directly from the scales. Should it become necessary to vary the composition of the gaseous mixture during the application thereof 95 the adjustment of the valves accomplishes the object almost instantaneously, the new composition of the mixture being apparent immediately by reference to the several legs and 100 the positions of the liquid therein. 105

These objects and advantages are attainable in the apparatus as illustrated and described and by the use of various modifications thereof without departing from the invention. 110

I claim:—

115 1. In an apparatus for producing mixtures of gaseous constituents in predetermined proportions, the combination of a plurality of pipes adapted to be connected separately to sources of the gaseous constituents under pressure, a mixing chamber directly communicating with the pipes, and liquid containing means including a common reservoir connected with the pipes and mixing chamber 120 and controlled by differential pressures in the pipes and mixing chamber to indicate the relative quantity of each gaseous constituent entering the mixture.

125 2. In an apparatus for producing mixtures of gaseous constituents in predetermined proportions, the combination of a mixing chamber, a plurality of pipes directly connected thereto and adapted to be connected separately to sources of the gaseous constituents 130

under pressure, a plurality of legs connected to the pipes, a liquid receptacle communicating with the legs and with the mixing chamber and means to maintain differential pressures between the pipes and mixing chamber whereby the liquid levels in the legs indicate the relative quantity of each gaseous constituent entering the mixture.

3. In an apparatus for producing mixtures of gaseous constituents in predetermined proportions, the combination of a mixing chamber, a plurality of pipes connected thereto and adapted to be connected separately to sources of the gaseous constituents under pressure, a plurality of legs connected to the pipes, a liquid receptacle communicating with the legs and with the mixing chamber and diaphragms having capillary openings between the pipes and the mixing chamber to maintain differential pressures whereby the liquid levels in the legs indicate the relative quantity of each gaseous constituent entering the mixture.

4. In an apparatus for producing mixtures of gaseous constituents in predetermined proportions, the combination of a plurality of pipes adapted to be connected separately to sources of the gaseous constituents under pressure, a mixing chamber directly communicating with the pipes, means connected with the pipes and mixing chamber and controlled by differential pressures in the pipes and mixing chamber to indicate the relative quantity of each gaseous constituent entering the mixture, and a vane in the mixing chamber to cause the gaseous constituents to mingle therein.

5. In an apparatus for producing mixtures of gaseous constituents in predetermined proportions, the combination of a mixing chamber, a plurality of pipes connected thereto and adapted to be connected separately to sources of the gaseous constituents under pressure, a plurality of legs connected to the pipes, a liquid receptacle communicating with the legs and with the mixing chamber, means to maintain differential pressures between the pipes and mixing chamber whereby the liquid levels in the legs indicate the relative quantity of each gaseous constituent entering the mixture, and means to maintain a constant level of the liquid in the liquid receptacle.

In testimony whereof I affix my signature.
LLOYD K. RIGGS.
